UNITED STATES PATENT OFFICE.

HARRISON W. PRICE, OF PITTSBURG, PENNSYLVANIA.

SIGNAL.

SPECIFICATION forming part of Letters Patent No. 772,631, dated October 18, 1904.

Application filed June 22, 1903. Serial No. 162,567. (No model.)

To all whom it may concern:

Be it known that I, HARRISON W. PRICE, a citizen of the United States, residing at Pittsburgh, in the county of Allegheny and State of Pennsylvania, have invented a new and useful Improvement in Signals, of which improvement the following is a specification.

This invention relates to certain new and useful improvements in railway danger-signals, and relates more particularly to that class of signals which are used at grade-crossings to indicate the approach of a train.

The object of this invention is to provide a signal which will be cheap in construction and operated by mechanical means.

With the above and other objects in view the invention resides in the novel arrangement and combination of parts, which will be hereinafter more fully described, and specifically pointed out in the claim.

In describing the invention in detail reference will be had to the accompanying drawings, which form a part of this specification, wherein like reference characters designate like parts throughout both views, in which—

Figure 1 is a plan view showing the arrangement of my signal. Fig. 2 is a side elevation of the same.

The reference-numeral 1 indicates the track, 30 and 2 the alarm-signal station placed at one side thereof adjacent to the track at the crossing. At a suitable distance from the crossing the operating mechanism is placed, the said mechanism consisting of the trip-lever 3, 35 which is secured to the rock-shaft 4, preferably inside and close to the rail. This trip-lever extends slightly above the rail in such a manner that the shaft 4 is rocked as each wheel of a train passes over and depresses 40 the lever 3. The outer end of the shaft has an actuating-crank 5 secured to it, and the shaft is mounted in bearings 6, secured to the ties. The signal-tower has uprights 7, 7, in the upper end of which the shaft 8, carrying the alarm-bell 8', is mounted, and a crank 9, secured to said shaft, is connected to the bell-crank 10 by the link 11. A spring 45 12 holds the bell in position to be operated and restores the parts to their operative position after each operation of the parts. The bell-crank 10 is connected with the crank 5

by means of a rope, wire, or lever 13, the said wire, rope, or lever being preferably placed in a suitable conduit 14, and a roller 15 confines said rope 13 at a point adjacent to the crank 5 for the purpose of obtaining the full benefit of the movement of the crank 5.

The operation of the device would be as follows: The wheels of a train passing over and depressing the lever 3 will actuate the 60 crank 5, thus tilting and ringing the bell through the medium of the rope, wire, bell-crank, lever, and crank.

While I have herein shown and described my invention in detail, it will be obvious that 65 various slight changes may be made in the same without departing from the general spirit of my invention.

Having fully described my invention, what I claim as new, and desire to secure by Letters 70 Patent, is—

A device of the type set forth consisting of a rock-shaft, with bearings therefor supported by the cross-ties, said shaft carrying a trip on its one end located adjacent one of the 75 rails, and a crank on its other end, uprights mounted adjacent the track and at a point a considerable distance away from said rock-shaft, with a shaft carried by the uprights at the upper ends thereof, an alarm-bell mounted 80 on the shaft, and a crank carried by the shaft, a link connected to the crank, a bell-crank supported by the uprights adjacent the lower end thereof, and having one of its ends connected to said link, a spring connected to 85 said link and to one of the uprights, and a flexible connection between the other end of said bell-crank and said crank of the rock-shaft, a conduit inclosing said flexible connection with the roller supported by the latter and located above the flexible connection 90 by which it is engaged, said roller being located in alinement with the upper end of said rock-shaft crank, said flexible connection normally extending in the same plane throughout. 95

In testimony whereof I have hereunto signed my name in the presence of two subscribing witnesses.

HARRISON W. PRICE.

In presence of—

F. O. HENZI,
H. J. LEVIS.
